UNITED STATES PATENT OFFICE.

JAMES T. McDERMOTT, OF WORCESTER, MASSACHUSETTS.

RELAY AND AMPLIFIER.

Application filed December 27, 1921. Serial No. 524,871.

To all whom it may concern:

Be it known that I, JAMES T. McDERMOTT, a citizen of the United States, residing at Worcester, in the county of Worcester and 5 State of Massachusetts, have invented a new and useful Relay and Amplifier, of which the following is a specification.

This invention relates to a relay and amplifier for telephone and telegraph circuits. 10 It can be applied to wireless telephony and telegraphy.

The principal objects of the invention are to provide a relay and amplifier that will reproduce either conversation, music, or dot-and-dash signals, or in fact any sound, with a very great increase in loudness; and to provide such a device in a simple form, which by slight modifications can be used either for telegraphy or telephony and also 20 for wireless.

Further objects and advantages of the invention will appear hereinafter.

Reference is to be had to the accompanying drawings, in which

25 Fig. 1 is a wiring diagram showing the invention as used for receiving and amplifying signals by wireless telegraphy;

Fig. 2 is a plan of the instrument itself;

Fig. 3 is a fragmentary end view with 30 parts in section;

Fig. 4 is a side view partly in section, and

Fig. 5 is a wiring diagram showing a modified form of the invention used for a telephone circuit.

35 Referring first to the first four figures, I have shown the invention as connected up with an ordinary wireless telegraph circuit comprising any desired form of antennae 10 connected in series with a tuner 11, the secondary of which is connected by a detector or amplifier 12 with an ordinary telephone receiver 13. This receiver may be of any ordinary kind, such for example as a Baldwin receiver which is well known on the market. I also provide the tuner with two variable condensers 14 for adjustment.

40 The receiver 13 shown is one which is provided with a diaphragm 20 provided at the rear with a wire 21 which is connected yieldingly with the magnet inside, but this type of receiver is not essential. I provide the outer side of the diaphragm with a fastening means 22 of any desired character and to this is connected a brass pin or staple 23. With this pin is connect-

ed a flexible member, preferably in the form of a waxed silk thread 24, which at the other end is connected with a vibratory arm 25. This arm is pivoted on adjustable pivot studs 26 so as to avoid any looseness at the 60 pivots. A spring 27 is used preferably to hold the arm over to one side toward an adjusting screw 28.

The actual connection of the waxed silk thread 24 with this arm 25 is made by two 65 springs 30 and 31. The spring 31 is farthest at the rear and is directly connected with the end of the thread. Each of the springs is held to the arm 25 by a screw 32 extending into a slot in the end of the spring and 70 holding this end flat against the arm. They are arranged at an angle crossing each other and the inner spring 30 has its end bearing on the upper end of the arm 25. In this way the thread is held yieldingly and yet 75 it positively moves the arm when the diaphragm 20 moves inwardly.

To move the arm in the other direction it is provided with a connection 35 which is connected by a spring 36 with a rotatable 80 adjusting screw 37 by means of a flexible cord 38. This cord 38 is wound around the adjusting screw 37 which screws into a post 39 and is provided with a head 40 or the like for operating it and a check nut 41 for 85 holding it. The desired amount of tension can be applied to the arm 25 to hold the thread 24 exactly taut and yet not unduly stretch it or strain the diaphragm 20.

The arm 25 is provided with a platinum 90 point 42 adapted to make and break contact with a platinum point 43 mounted on an adjusting screw 44 on a frame 45. This frame is shown as of goose-neck form and having on the opposite side an adjusting, 95 screw 46 for adjusting an insulating stop 47 toward and from a projection 48 at the rear of the arm 25.

When contact is made between the points 42 and 43 by the inward motion of the diaphragm 20 a current is set up in a relay circuit from the screw 44 to a buzzer 50, through a dry battery 51 back to the bracket on which the adjusting screw 28 is located, and thus back to the vibratory arm 25, 105 which, of course is of conducting material. The buzzer I have found should be provided with a choking coil, and I have shown in this case a small incandescent lamp 52 used for this purpose. This lamp will glow 110

when the current is passing, of course, and therefore gives a visible signal which can be read by an observer in addition to the audible signal.

5 I have found that by this arrangement the buzzer will give a complete and perfect reproduction of any telegraphic message that may be received by the wireless apparatus with an increase in loudness of several 10 hundred per cent if properly tuned and adjusted. I also find that without change of apparatus, but by mere changes in adjustment and tuning, very wide range of wave lengths can be detected and transmitted.

15 The device is not limited to telegraphy however, and I have shown in Fig. 5 a modification in which the device can be used for telephone purposes. Here I have shown the Baldwin receiver 13 as connected up 20 with a circuit 60 which may be from a detector or amplifier or an ordinary telephone circuit. The receiver is connected with the vibratory arm 25 in the same way as shown in Fig. 1, which transmits all sounds 25 through a telephone circuit 61, having a battery 62 therein, to a telephone transformer 63 and secondary circuit 64 provided with a telephone receiver 65. The only changes necessary in this case are a different degree 30 of adjustment and tuning, and the provision of a carbon terminal 67 in place of the platinum terminal 43.

35 It is to be noted that in Fig. 5 I have shown the instrument in what I call vertical instead of horizontal position. In this case the springs 36 supports the weight of the arm 25 and I have found in practice that the instruments, at least those that I have actually built, act more satisfactorily 40 in this position than in the horizontal position. The transmission seems clearer and more nearly perfect.

45 I have found that such an instrument is very effective in telephony and will transmit an ordinary telephone message so loudly that it is impossible for the receiving operator to hold the receiver 65 to the ear. Such a device will transmit an ordinary conversation or music with sufficient loudness 50 to enable it to be heard distinctly all over a good sized room, and it will also receive wireless telephone conversation and transmit it clearly enough to be heard by the user of the receiver 65 in the ordinary way.

55 It is apparent, therefore, that this amplifier is capable of a wide range of use and is not limited to any particular type of telegraphy or telephony.

60 Although I have illustrated and described only two embodiments of the invention I am aware of the fact that modifications can be made therein by any person skilled in the art without departing from the scope of the invention as expressed in 65 the claims.

Therefore, I do not wish to be limited to all the details of construction herein shown and described, but what I do claim is:

1. In a relay and amplifier for interrupted electric circuits, the combination 70 with a telephone receiver connected with the receiving circuit for transmitting the messages delivered thereto, of a vibratory arm mounted to be capable of free vibration, insulating flexible means for connecting 75 said arm with the vibratory part of said receiver, yielding means acting in one direction only for constantly pulling the arm away from the receiver to keep said flexible means taut, a pair of terminals, one mounted 80 to move with said arm, and the other located in position to be engaged thereby, and a secondary circuit connected with said terminals and comprising means for receiving signals transmitted by the contact and separation of said terminals. 85

2. In a relay and amplifier for interrupted electric circuits, the combination with a 90 telephone receiver therein having a vibratory member, of a non-conducting flexible member connected with said vibratory member, a vibratory arm to which the other end of said flexible member is connected, means connected with said arm for constantly but yieldingly forcing it away from 95 the receiver, means for adjusting the tension of said yielding means, a terminal on said arm, an adjustable terminal in position to be engaged by the first named terminal, and a circuit connected with said terminals. 100

3. In a relay and amplifier for interrupted electric circuits, the combination with a 105 telephone receiver therein having a flexible diaphragm, of a pliable member connected with the center of said diaphragm and extending from it at right angles to its surface, a vibratory arm to which the other end of said flexible member is connected, a 110 spring on the other side of said arm, means for adjusting the tension of said spring, a terminal on said arm, a terminal in position to be engaged by the first named terminal, and a circuit connected with said terminals. 115

4. In a relay and amplifier for interrupted electric circuits, the combination with a telephone receiver therein having a flexible diaphragm, of a flexible member connected with said diaphragm, a vibratory arm to which the other end of said flexible member is connected, a spring connected with 120 said arm, means for adjusting the tension of said spring, a terminal on said arm, a terminal in position to be engaged by the first named terminal, and a circuit connected with said terminals. 125

5. In a relay and amplifier for interrupted electric circuits, the combination with a telephone receiver therein having a diaphragm, of a flexible member connected with said diaphragm, a vibratory arm to which the 130

other end of said flexible member is connected, a terminal on said arm, a terminal in position to be engaged by the first named terminal, and a circuit connected with said 5 terminals.

6. A relay and amplifier for an interrupted electric circuit comprising a telephone receiver connected up for receiving signals, and comprising a flexible diaphragm, a waxed silk thread connected with said diaphragm, a freely pivoted vibratory arm to which said thread is connected, a spring connected with the opposite side only 10 of said arm for always pulling the arm away from the diaphragm and keeping the thread taut, means for adjusting the tension of said spring, a spring on the arm opposite the first named spring and having a 15 terminal thereon, a frame on which is a terminal adapted to be engaged by the terminal thereon, a frame on which is a 20 terminal adapted to be engaged by the terminal on the arm when the diaphragm

moves inwardly, an adjustable insulated stop on the opposite side of said arm and mounted on said frame, and a transmitting circuit connected with said terminals. 25

7. A relay and amplifier for an interrupted electric circuit comprising a telephone receiver connected up for receiving signals, and comprising a flexible diaphragm, a waxed silk thread connected with 30 said diaphragm, a freely pivoted vibratory arm to which said thread is connected, a terminal thereon, a frame on which is a terminal adapted to be engaged by the terminal on the arm when the diaphragm 35 moves inwardly, an adjustable insulated stop on the opposite side of said arm, and a transmitting circuit connected with said terminals.

In testimony whereof I have hereunto af- 40 fixed my signature.

JAMES T. McDERMOTT.
